INVENTOR:
PHILIPP SCHNEIDER.

W. L. Dugay
ATTORNEY.

BY

UNITED STATES PATENT OFFICE.

PHILIPP SCHNEIDER, OF ST. LOUIS, MISSOURI.

PUNCH.

Application filed February 21, 1927. Serial No. 169,904.

My invention relates to punches, and especially to that class of punches used by sheet metal workers.

The object of my invention is to provide a punch in which the bit, or point, can be removed readily and quickly, and renewed.

Other objects and advantages of my invention will be apparent from the specification, claim and drawings, in which:—

10 Fig. 1 is a perspective view of my punch.

Fig. 2 is a like view, partly broken away and in section.

Fig. 3 is a plan view of the detachable head.

15 Fig. 4 is a longitudinal section of the detachable head, showing the punch point in place.

Fig. 5 is a view of a punch press, showing the use of my punch.

20 When punching a hole through sheet metal, in order that a clean hole be punched and a portion of the metal cut away of a diameter equal to the diameter of the punch, it is necessary that the point of the punch

25 have a plane, flat surface and that the periphery of the flat surface be substantially at right angles to the plane thereof, in order that the punch may cut a clean hole with a shearing effect.

30 It is readily understood that the continued use of a metal punch, however well hardened, in punching holes through metal, the corners of the punch become worn and rounded, making it necessary to stop and re-

35 grind and repair the point. This causes unnecessary and expensive delay; and to avoid this objection I have devised a method by which a point when dull may be readily removed and a new one inserted at a minimum

40 expenditure of time and labor.

My improved punch is preferably made of an outer cylindrical body 1 screw-threaded at its lower end 2 adapted to engage a like screw-threaded portion in the nut 3, 45 which may be hexagonal, quadriangular, or other suitable shape that will permit the nut to be rotated by a wrench or other suitable tool.

The nut 3 has its upper portion screw-threaded, as designated at 4, a sufficient distance from its upper end to securely hold the body portion 1 when screwed into the nut.

The walls 5 of the lower portion of the

nut 3 are sloped downwardly and inwardly so as to leave a cone-shaped opening therein.

The bit holder consists of a body 6, perforated through its longitudinal center adapted to fit closely a bit 7, which is inserted through the top end of body 6 of the bit holder, the bit being provided with a flanged head 8 to prevent its dropping through.

A plurality of longitudinal slots 9 are provided at the lower portion of the body 6 of the bit holder adapted to be closed together so as to clamp the bit when the body of the holder is forced downward by the cylindrical body 1 being screwed into the nut 3.

70 A solid, cylindrical anvil 10 is inserted in the hollow cylindrical body 1 and projects upwardly beyond the top of the cylindrical body 1, and its lower end presses firmly upon the top of the bit 7, thus when a blow is struck upon the top of the anvil 10, the force of the blow is imparted only to the bit 7.

75 It is quite obvious that I have greatly increased the efficiency of a sheet metal worker's punch by being able to supply a number of detachable bits that can be readily and quickly attached to and detached from the punch and a new, sharp bit be inserted in lieu thereof.

80 In Fig. 5 the use of my invention when applied to a hand-operated punch press is shown. It could, of course, be as readily adapted to power presses.

85 Having fully described my invention, what I claim as new and useful and desire to secure by Letters Patent is:—

A punch of the class described, comprising a hollow frusto-conical-shaped bit holder having its lower portion longitudinally slotted adapted to fit a conic opening in a nut, a screw-threaded, hollow, cylindrical portion adapted to be screwed into said nut thereby tending to force the said frusto-conical bit holder outwardly, a solid cylindrical anvil adapted to reciprocate in said hollow, screw-threaded, cylindrical portion when struck by a hammer thereby imparting energy to a bit enclosed in said frusto-conical bit holder, a bit having a flanged head, said bit being adapted to be rigidly held in said frusto-conical bit holder when said cylindrical body portion is screwed

into said nut, a nut having its upper portion screw-threaded adapted to engage the screw-threaded portion of the said cylindrical portion, and an opening in its lower portion having sloping walls adapted to fit the periphery of the said frusto-cone-shaped, slotted bit holder and adapted to rigidly

hold a bit when said cylindrical portion is tightly screwed into said nut.

In witness whereof I have hereunto affixed my signature this 6th day of January, 1927.

PHILIPP SCHNEIDER.
